Primary Examiner — Mark A Goodwin(74) *Attorney, Agent, or Firm* — Geeta Kadambi; Riddhi IP LLC(57) **CLAIM**

The ornamental design for “autonomous electric tractor”, as shown and described.

DESCRIPTION

FIG. 1 is a first perspective view of the autonomous electric tractor.

FIG. 2 is a second first perspective view of the autonomous electric tractor.

FIG. 3 is a third back perspective view of the autonomous electric tractor.

FIG. 4 is a fourth right side perspective view of the autonomous electric tractor.

FIG. 5 is a fifth left side perspective view of the autonomous electric tractor; and,

FIG. 6 is a sixth top down perspective view of the autonomous electric tractor.
